US00D537804S

(12) **United States Design Patent** (10) **Patent No.:** **US D537,804 S**
(45) **Date of Patent:** **** Mar. 6, 2007**

(54) **PORTABLE TELEPHONE**

(75) Inventors: **Dae-Yoeb Park**, Seoul (KR);
Chang-Hwan Hwang, Kyungki-Do (KR); **Chi-Young Ahn**, Seodaemun-Gu (KR)

(73) Assignee: **Samsung Electronics Co., Ltd.**, Suwon-si (KR)

(**) Term: **14 Years**

(21) Appl. No.: **29/230,669**

(22) Filed: **May 25, 2005**

(51) **LOC (8) Cl.** **14-03**

(52) **U.S. Cl.** **D14/138**

(58) **Field of Classification Search** D14/341-347, D14/138, 137, 147, 128; 455/575.1, 575.3, 455/575.4, 90.3, 556.1, 556.2; 379/433.01-433.13; 361/814

See application file for complete search history.
